Inventor.

F. L. Gibbs

United States Patent Office.

D. L. GIBBS, OF WORCESTER, MASSACHUSETTS, ASSIGNOR TO R. BALL AND COMPANY, OF SAME PLACE.

Letters Patent No. 86,389, dated February 2, 1869.

IMPROVEMENT IN MORTISING-MACHINES.

The Schedule referred to in these Letters Patent and making part of the same.

Know all men by these presents:

That I, D. L. GIBBS, of the city and county of Worcester, and Commonwealth of Massachusetts, have invented certain new and useful Improvements in Mortising-Machines; and I do hereby declare that the following is a full, clear, and exact description of the same, reference being had to the accompanying drawings, forming a part of this specification, in which—

Figure 1 represents a front view of my improvements in mortising-machines.

Figure 2 represents a view of the right-hand side of my improved mortising-machine.

Figure 3 represents a rear view of the same.

Figure 4 represents a central section on line A B, fig. 1.

Figure 5 represents a horizontal section on line C D, fig. 2.

Figure 6 represents a plan view of the chain-wheel and hand-lever, the wheel being made somewhat differently from the one shown in the previous drawings.

Figure 7 represents a front view of the chain-wheel and hand-lever shown in fig. 6.

To enable those skilled in the art to which my invention belongs, to make and use the same, I will proceed to describe it more in detail.

The nature of my invention consists—

First, in the peculiar combination and arrangement of devices for turning or reversing the chisel, as hereafter described.

Second, in the arrangement of mechanism, as hereafter described, for reversing the chisel in mortising-machines, so that the same may be operated either by power or by hand.

Third, in the arrangement of certain devices, in the peculiar manner shown and described, for connecting the treadle-rod to the treadle, whereby the length of the stroke may be regulated, as hereafter set forth.

Fourth, in the arrangement, in a power-mortising machine, of the devices shown in the drawings, as and for the purposes hereafter described.

In the drawings, the part marked A is the main frame, B, the driving-shaft, and C, the crank-wheel, all of which are constructed in the usual form and manner, and will therefore need no further explanation.

Upon the front part of the main frame A is arranged the slide D, carrying the chisel-spindle E, the former being operated up and down, between its guides F, by means of the connecting-rod G from the crank-wheel C.

The chisel-spindle E is supported by bearings D', projecting from the slide D, and bearings H are secured to the faces of the guides F, which support the belt or chain-wheel K, by means of which the chisel-spindle E is reversed.

The chain-wheel K is furnished with a spline, which fits into a longitudinal groove cut in the side of the spindle E, and its outer surface may be made with a groove

around it, as shown in fig. 4, or with projecting points a, as indicated in figs. 6 and 7, to fit between the links of the chain, and prevent it from slipping upon the surface of the wheel, when a chain is used.

Below the pointed or grooved portion, in the face of the wheel K, at opposite points, are formed two notches, c, into which the end 2 of a catch-lever, I, enters, to hold the wheel K and chisel-spindle E in position while the mortises are being cut.

A hole, b, is also made in the face of the chain-wheel, to receive the handle d, when it is desired to reverse the chisel by hand.

Pins are placed in the notches c to receive the wear caused by the end 2 of the catch-lever I, and they can be easily replaced when worn out.

The catch-lever I is hung upon a pivot, e, secured in the side of the main frame A, and made adjustable by a set-screw, f.

The upper end of lever I is projected backward, forming a beak, g, and the lower end, 2, projects forward, and passes through a slot cut for that purpose in the slide D, where it is held in contact with the chain-wheel K, by means of a spring, J, secured to the front of the main frame A, and resting against the top end of the lever I, all of which is fully indicated in the drawings.

In the interior of the main frame A, near the back, is placed a pulley, L, having, in this instance, upon its surface several grooves, and when the pointed chain-wheel is used, it also has rows of points similar to those upon said wheel.

The pulley turns upon a stud, M, secured to a forked support, N, by a nut, M', and by means of which the stud M may be adjusted back and forth, to tighten the belt, or chain m, which transmits motion from the pulley L to the chain-wheel K and chisel-spindle E.

The forked support N is secured to the main frame A, and made adjustable up and down by having fastened to its rear end, slotted ears N', which extend outward upon the back of the frame A, and through which pass bolts or screws h, as indicated in the drawings.

The pulley L derives its motion from a pulley, O, upon the driving-shaft B, by means of a belt, p, which passes down under grooved pulleys n, placed at the sides of a stud, P, which projects from the rear of the machine.

The stud P is cast upon a plate, O', that is formed with slots i, through which the bolts or screws k pass, that secure it to the main frame A, and it is thereby made adjustable.

Holding-pins, x, are placed in the sides of the stud P, outside the grooved pulleys n, to prevent the belt p from being thrown off.

Secured to the treadle-rod Q, which connects the treadle R with the bearing frame, B', of the driving-shaft B, is an adjustable collar, or slide, S, to the top side of which is pivoted a dog, t, as shown in fig. 4.

When the treadle-rod is moved down, the point of the dog rises, which allows it to pass freely by the beak *g*, at the end of the catch-lever *I*, but when the treadle-rod *Q* rises, the point of the dog engages the beak *g*, and throws it forward, which operation moves the lower end of the catch-lever *I* out of the notch *c*, upon the chain-wheel *K*, and allows it to turn.

The lower end, 2, of the catch-lever *I*, may also be moved back by the hand-lever *T*, which is pivoted to the plate *U*, fastened to the side of the main frame *A*, through which the hand-lever *T* passes, with its end resting against the front side of the catch-lever *I*, and by means of which the latter can be held back, by drawing the outer end of the hand-lever *T* forward, and retaining it in that position by the latch *w*, as indicated in red lines, fig. 5.

Projecting from each side of the main frame *A* are latch-pieces *u*, which hold the chisel in position when the reversing is performed by hand, with the handle *d*.

At the lower end of the treadle-rod *Q* is a collar, *V*, against which presses the spring *S'*, which holds the working-parts of the machine in an elevated position.

An adjusting-device is arranged at the lower end of the treadle-rod *Q*, which consists of two metallic plates, *W* and *Z*, one of which is attached to the end of the treadle-rod *Q*, and the other is pivoted to the treadle *R*. Their joining faces are serrated, and they are clamped together by a bolt or screw, *y*, the plate *Z* being slotted to admit of its being clamped in different positions, to adjust the treadle to the desired position to be operated conveniently, and with the greatest ease to the operator, while cutting mortises of different depths.

When the mortises to be cut are of great depth, a long stroke of the treadle is required; therefore the plates *W* and *Z* are clamped together, with the lever at the highest position to which it can be raised, thus giving the full sweep of the treadle from top to bottom of the opening. But when the mortises are to be shallow, the plates *W* and *Z* are clamped with the treadle, but partially raised, according to the depth of mortise required, thereby obviating the necessity of the operator raising his foot any higher than is actually required to clear the chisel from the mortise. In this manner much time and labor are saved.

Bars *3* are arranged across the interior of the frame *A*, to prevent the treadle-rod *Q* from springing, and allowing the dog *t* to pass the beak of the catch-lever without engaging and operating it.

The operation is as follows:

The machine being in motion, the treadle *R* is pressed down, which allows the dog *t* to pass beneath the beak *g* of lever *I*, and also loosens the belt *p*. Then, when the mortise is cut far enough in that direction, the pressure is removed from the treadle *R*, and the driving-shaft and pulley *O* being raised by the power of the springs *S*, the belt *p* is tightened, so that it will operate pulley *L*, and at the same time the dog *t*, in passing the beak *g*, throws the lower end, 2, of the catch-lever *I*, for an instant, out of the notch *c* in the chain-wheel *K*, which is, with the spindle *E*, turned

by means of the belt or chain *m*, around until the catch-lever *I* enters the next notch upon the face of the chain-wheel *K*, which being at the opposite side, reverses the chisel-spindle *E* and chisel.

When, from accident or otherwise, it becomes necessary to reverse the chisel by hand, the belt or chain *m* is thrown off from the chain-wheel *K*, the catch-lever *I* is latched back, and the handle *d* screwed into the opening *b*, as shown in red lines, fig. 5. Then, by moving the handle *d* from side to side, the chisel-spindle is reversed, and held in position by latching the handle *d* in the notches at the under side of the projecting pieces *u*, which may be easily done, as the handle is made flattened to form a spring, as shown in figs. 6 and 7.

In case it should be desired to reverse the chisel when the parts are in position, as shown in fig. 4, the operator has only to draw the hand-lever *T* forward, as indicated by red lines, fig. 5, and the chisel will be automatically reversed, by means of belt *p* and belt or chain *m*, operating as before explained.

Having described my improvements in mortising-machines,

What I claim therein as new, and of my invention, and desire to secure by Letters Patent, is—

1. The combination, with the chisel-spindle *E*, and pulley *K*, and belt or chain *m*, of the pulley *L* and belt *p*, substantially as and for the purposes stated.
2. The combination, with pulley *L*, grooved pulleys *n*, and driving-shaft *B*, of the belt *p*, substantially as and for the purposes set forth.
3. The combination, with belt *p* and grooved pulleys *n*, of holding-pins *x*, as and for the purposes shown and described.
4. The arrangement of the spindle *E* and wheel *K* with catch-lever *I* and spring *J*, substantially as and for the purposes stated.
5. The combination, with treadle-rod *Q* and catch-lever *I*, of the hinged dog *t*, collar or slide *S*, either fixed or adjustable, substantially as shown and described.
6. The arrangement, with treadle-rod *Q*, of the steadyng-bars *3* and hinged dog *t*, as and for the purposes stated.
7. The arrangement of the chisel-spindle *E*, pulley *K*, catch-lever *I*, and hand-lever *T*, reversing-handle *d*, and latch-pieces *u* and *w*, substantially as and for the purposes set forth.
8. The arrangement of the sliding or bearing frame *B*, treadle-rod *Q*, treadle *R*, adjusting-clamp plates *Z* *W*, screw or bolt *y*, all the parts being constructed as shown and described.
9. The arrangement, with frame *A*, of the mechanism herein described, for reversing the chisel by power or by hand, as shown, and for the purposes set forth.

D. L. GIBBS.
